UNITED STATES PATENT OFFICE.

LAURENCE E. TOPHAM, OF WENHAM, MASSACHUSETTS, ASSIGNOR TO THE UNITED SHOE MACHINERY CORPORATION, OF PATERSON, NEW JERSEY, A CORPORATION OF NEW JERSEY.

MANUFACTURE OF LASTS.

Application filed February 7, 1923, Serial No. 617,603. Renewed October 1, 1926.

The present invention relates to the manufacture of irregular objects in accordance with a pattern, and is illustrated in connection with a machine for finishing the extremities of last parts.

Lasts are ordinarily turned in a copying lathe, where they are suspended upon dogs engaging their ends. It is impossible for the cutter to operate in the immediate vicinity of these dogs so that a "stub" is left on each end of the last which is generally finished off by hand at considerable expense and risk of inaccuracy. While a number of machines have been proposed for the mechanical performance of this operation, only one of them has reached the point of commercial use, and is attended with certain disadvantages, for example, that it will not grade a series of sizes and widths from a single model, so that there must be furnished a model for every size and width. From an economic standpoint, it is also a great disadvantage to the last maker to be obliged to invest in a separate machine of a type radically different from those of his other equipment, of greater cost and intricacy of construction, and which will be often idle.

Further, additional difficulty is introduced in dealing with the problem of the complete finishing of the ends of separate last fore and and heel parts, the independent manufacture of which is becoming important.

In view of these conditions, it is an object of my invention to provide an improved method and apparatus for the performance of turning operations, such as end-finishing operations on last parts and the like, by the utilization of which the above-mentioned and other disadvantages and difficulties may be avoided.

Accordingly, the invention provides a copying lathe arranged to hold a last part with its longitudinal axis (at the end of which the stub is formed) extending substantially perpendicularly to the work driving spindle, and to guard the cutter when passing around those parts of the work not treated in the machine.

In another aspect the invention provides a novel method of last making comprising automatically revolving the stub against a

cutter and guiding the work from a model or template to regulate the depth of cut. Preferably also, in accordance with the invention, the cutter is guarded as it passes around the work piece except at the stub.

Considering the invention again from the machine aspect, it provides for the organization of grading mechanism with the work treating apparatus as described above. In the disclosed machine, the grading mechanism of the lathe performs its ordinary functions upon that part of the work being treated. The feature of employing the cutter only at the stub portion of the last simplifies the grading problem very much, owing to the special nature of the cutting done, and advantage is taken of this to utilize an anomalous action of the width grading mechanism to accomplish the guarding of the cutter.

Moreover, while the illustrated machine is especially designed for performing turning operations on last parts as distinguished from lasts, and the objects operated upon by this machine are herein generally referred to for convenience as last parts, in various aspects the invention is not so limited.

These and other features of the invention comprising certain combinations and arrangements of parts will be understood from the following description of a preferred embodiment thereof selected for purposes of illustration and shown in the accompanying drawings in which,

Fig. 1 is a plan view of the machine;

Fig. 2 is a cross-section on the line 2—2 of Fig. 1;

Fig. 3 is a detail of the model and work holding fixture.

Fig. 4 is a detail illustrating the formation of the last parts.

Figs. 5 to 9 are diagrammatic details of the different cams used in the machine.

The machine shown is largely disclosed in my two prior applications Ser. No. 429,719, filed Dec. 10, 1920, and Ser. No. 530,214, filed Jan. 18, 1922, and reference may be made to them for description of parts not fully described herein. The main frame 10 supports three longitudinally sliding carriages 12, 14, 16. The carriage 12 carries

the cutter 18, and is connected to the carriage 14 by a right and left screw 20 for moving the carriages oppositely. The carriage 16 carries the model wheel 22, and is joined to the carriage 14 by a length grading mechanism 24 which may be of any desired type, as, for example, the regular Gilman apparatus.

10 The swing frame is a heavy square shaft 26 mounted on trunnions 28, and having three arms 30, 32, 34. The central arm 32 carries gearing to drive a spindle 36 on the ends of which are mounted two face plates 38 arranged to receive dog carrying fixtures 40 as explained in the latter of the above cited applications. The two outside arms 30, 34 also carry dogs 40. The spindle 36 (and dogs 40, if desired) is driven from a shaft 42, through gearing 44, shaft 46, and gears 48, as explained in detail in said application Ser. No. 530,214.

Arranged for mounting upon the face plates 38 are fixtures 50, 52 which, in the forms shown, extend across toward and engage the dogs 40, respectively. They are in the present instance arranged to cooperate with the joint surfaces of the last parts of the last invented by G. P. S. Cross, disclosed and claimed in his application Ser. 25 No. 465,951, filed May 2, 1921. It will be understood, of course, that the fixtures 50, 52 will be designed in any case to hold the particular last parts being treated, preferably by their joint surfaces, since these 30 are naturally in a definite relation to the external contour of the last and generally have a plane portion which cooperates readily with the fixture for accurate positioning. The fixtures shown have a portion 54 arranged to be keyed or otherwise firmly and definitely fastened to the face plates, and a carrying portion 56 arranged to hold the last part 58 or the model 59. The fastening of the last part is preferably effected 35 by similar mechanism to that used in bonding the last parts, and occupying the holes formed in the wooden last parts for this bonding mechanism. This secures accuracy of position. The carrier portions 56 are 40 so arranged, in any case, that the last parts (and model) is carried with its longitudinal axis (of the last as a whole) approximately perpendicular to the axis of the dogs and face plates, leaving the stub 60 projecting 45 directly away from the axis of rotation, so that it can be trimmed off in accordance with the shape of the model in the well-understood manner.

It will of course be unnecessary to apply 50 the cutter to the work except in the vicinity of the stub, and it is furthermore necessary to guard it in some way as it passes around the carrier portion 56, and the invention therefore provides means for relieving the 55 cutter of duty at the desired times. This

is done by a modification of the regular width grading mechanism, which will now be briefly described. The model wheel 22 is carried on a horizontal slide 62, operated by a link 64 whose rear end feeler 65 is adjustable on the fan-board 66 by a link 68, pivoted to it at 69, the lower end of which link 68 is adjustable along a segment 70 by a link 72 and arm 74. The fan-board oscillates on an axis at 75 and is operated by the link 77 connecting its lower end to the swing frame. The arm 74 is integral with a segment 76 operated by a worm shaft and handle 78-80. The mechanism is designed to effect ordinary width grading from a men's model 70 when the segment 70 occupies the position shown in Fig. 2, (this position varies somewhat for models of different girths), whereupon the setting of the mechanism at 78-80 75 in the ordinary manner will give the desired 80 grade. The segment 70 is pivoted at 82, and its radius is equal to the effective length of the link 68. Therefore the segment can be swung to a position 70' where its center occupies the same position 69' as that taken 85 by the pivot 69 at the time when feeler 65 at the end of the link 64 is on the center 75, and in this adjustment the width grade is zero irrespective of the setting of the link 68 on the segment. The segment 70 can be 90 swung from one position to another by an arm 84 integral with it and operated by a cam 86 mounted on a gear 88 operated by the main shaft 42 so as to rotate in the same 95 time as the model and work. This peculiar 100 width grading structure shown is more fully described and is fully discussed in its relation to regular and irregular width grading 105 in my cited application Ser. No. 429,719. The cam 86 shown herein is especially designed for the present problem.

The portion 90 of the cam holds the segment in normal width grading position, as shown. Now, since the link 68 is set, as shown, to the extremity of the segment—farther than it would ever be set in width grading—this allows the link 64 to fall to the bottom of the fan-board, when the cam 90 is operative, thus pushing the slide 62 far 110 out and taking the swing frame and work away from the cutter during the passage of the model wheel around the part 56 and the already prepared lateral periphery of the last part. When, however, the end of the 115 last part is turned toward the cutter, the portion 92 of the cam, which is preferably a circle around its rotational center, moves the segment 70 into the position 70' concentric with the special position of the center 69', above mentioned which, in accordance with 120 the design shown, moves the end of the link 64 to the axis 75, irrespective of the adjustment of the link 68. The machine is then set for 1:1 reproduction and the stub 60 is 125 trimmed off. I have found that no practical 130

difficulty is experienced in cutting against the grain of the wood on one side of the last part, provided the cutters are kept sharp and rotated at high speed (preferably above 6000

5 R. P. M.) to insure the taking of small chips.

Width grading can be accomplished in connection with the removal of the stub, by a variant of the described construction. Instead of designing the stub turning cam por-

10 tion 92 to turn the segment 70 into the position where its center will fall on the fan-

board axis 75, it may be designed as shown at 92^a, Fig. 6, with the same radius as that

15 shown for the cam 90, while the cam 90 is made of considerably shorter radius, as

shown at 90^a in Fig. 6. Then the stub cutting cam 92^a will throw the segment into the

position shown in Fig. 2 corresponding to ordinary width grading, when the proper

20 setting of the mechanism at 78—80 will effect the ordinary performance of the width

grading mechanism, and the shorter radius guard cam 90^a will still pull the feeler 65

25 down to the bottom of the fan-board when the cutter goes around the fixture 52. This

procedure will not work, however, except when an actual increasing or "upward" grade is desired. If 1:1 reproduction were

30 sought, as first above described, the mecha-

nism at 78—80 when set at zero would set the lower end of the link 68 on the center 82,

in which case there would be no way thus far disclosed of effecting the movement of the slide 62 which guards the cutter during its

35 passage around the part 56. With the dis-

closed mechanism the lower end of the link 68 must be set off from the center 82 at all

times when it is necessary to guard the

40 If a diminishing or "downward" width grade is desired, the procedure above out-

lined would set the link 68 over to the other side of the pivot 82, and thus would grade the end properly, but when the cam portion

45 90^a came around, the slide 62 would fall very far back instead of forward, and the cutter would be ruined on the holder 52. This problem can be solved by using the

50 stub cutting cam 92^a in connection with a guard cam 90^b of diameter substantially

larger than that of the cam 92, (see Fig. 7) and in this case the grader settings at 80

will have their regular and apparent mean-

55 ings. The grading problem can also be dealt with as follows:—In grading up, the link

60 68 will be set on the left side of the center 82, (as seen in Fig. 2), and the stub cutting cam will be formed as shown at 92^c in

Fig. 8, of greater radius than 92, to pull the

65 feeler down below the center 75 in spite of the link setting. The guard cam will be formed as at 90^c, of still greater diameter, to pull the feeler down farther. The grader setting here, however, is purely empirical.

65 The machine will look superficially as if it

were set to grade down. In grading down, the link 68 will be set on the right side of the center 82; the stub cutting cam will be formed as at 92^d in Fig. 9, of greater diameter than 92, to lift the feeler above the 70 center 75 and the guard cam as at 90^d, of less diameter than 90, to drop it way down, the grading setting being again empirical. In short, the grading problem can be solved by making the radii of the guard and stub cutting cams both greater or both less than that of 92 for increase grading and one greater and the other less than that of 92 for decrease grading, 92 being defined as above, and 90 being extreme enough in radius to 80 guard the cutter.

It should be understood that what is really being done to the last part by the width mechanism is length grading, since the last

85 part is turned around with its natural longitudinal axis at right angles to its axis of rotation in the swing frame. The remarks above made in respect to the "regular and apparent meaning" of the grader setting refer to the magnification factor produced

90 thereby, which is to be the same as that used in length grading the last part in the original turning operation. In turning off the stub the length grader will preferably be set

95 to magnify at the same rate as the width grader in the original turning operation. The base of the stub is a long narrow line at

the end of the heel part or a small circle at the end of the toe, and while in some cases

100 the original relation between the length and width grading may not be exactly repro-

duced at all points of a horizontal section through the stub base, the base is so narrow that no practical difficulty is encountered.

The term "horizontal" here means parallel

105 to the floor when the last is in its normal position on the floor.

The terms "width grading" and the like

have been used in the claims as referring to magnification perpendicular to the axis of

110 rotation in the machine. That is, such terms refer to the action of the machine as known by such terms, rather than to the effect produced in the work, as ordinarily termed.

The cutting of the last parts themselves

115 is illustrated in Fig. 4 and will be clear with-

out more explanation than the statement that the dogs 102, 104 are likewise arranged

120 to be fastened to the face plates and to co-

perate with the joint surfaces prepared on the model and block, but holding them in

normal position in the lathe.

The guarding of the cutter from the metal

125 holder 52 can of course be accomplished by making the holder 50 oversize, but this is

not generally sufficient for the production of good work, as the model wheel rolls from the holder 50 to the model with a bump

130 which will cause the cutter to spring into the work a little, unless there is a further guard-

ing action. The cam surface 90, therefore, preferably holds the cutter away from the work over a period of some $\frac{3}{4}$ revolution at least.

- 5 In this connection, the total number of such holders required is of some interest. If the attaching means (holes, bolts, or whatever it may be) is the same for both right and left last parts, only one pair of 10 holders is necessary, of which one can be made larger than the other. If, on the other hand, different holders are required for right and left last parts, one pair will still do if the guarding of the cutter is done by 15 the width grading mechanism; but if the model holder is to be the larger, two pairs will be required.

The mechanism 97, 98, 99, 100 for holding the model wheel center in the plane containing 20 the spindle 36 and the cutter center will be found fully described in my application Ser. No. 530,214.

In the illustrated embodiment of the invention, the last parts are separately formed, 25 but the invention as disclosed is equally applicable to last parts which are severed after the whole last is turned in the ordinary manner.

Having fully described my invention, 30 what I claim as new and desire to secure by Letters Patent of the United States is:—

1. That improvement in the art of manufacturing lasts which consists in automatically revolving the stub, left after the turning 35 operation, about an axis transverse to the longitudinal axis of the last, against a cutter and guiding the work from a model to regulate the depth of cut.

2. That improvement in the art of manufacturing lasts which consists in revolving 40 the stub, left after the turning operation, about an axis transverse to the longitudinal axis of the last, against a cutter, guiding the work from a model, and guarding the cutter 45 as it passes around the work piece except at the stub.

3. A copying lathe having a tool and a 50 revoluble work support arranged to hold a last part with its longitudinal axis extending substantially perpendicularly to the drive spindle of the support, and means for holding the work out of contact with the cutter except at the stub.

4. A shoe last cutting lathe having a tool 55 and a revoluble work support arranged to hold a work piece with its terminal stub projecting substantially perpendicularly to the drive spindle of the support, and means for holding the work out of contact with the cutter except at the stub, comprising a non-pantographic width grading mechanism.

5. A copying lathe having a tool and a 60 revoluble work support, arranged to hold a last part with its longitudinal axis extending substantially perpendicularly to the

drive spindle of the support, and means for holding the work out of contact with the cutter except at the stub, comprising a width grading mechanism and a cam for grossly increasing the width grade except at the 70 stub.

6. A copying lathe having a tool and a revoluble work support, arranged to hold a last part with its terminal stub projecting substantially perpendicularly to the drive 75 spindle of the support, and means for holding the work out of contact with the cutter except at the stub, comprising a width grading mechanism and a cam constructed and arranged to throw the cutter relatively outside the contour of the work and work support except at the stub.

7. A copying lathe having a tool and a revoluble work support arranged to hold a last part with its terminal stub projecting 80 substantially perpendicularly to the drive spindle of the support, and means for holding the work out of contact with the cutter except at the stub, comprising a grading slide, a fan-board and a feeler between the 85 slide and the fan-board, and means for setting the feeler farther from the center of the fan-board when the tool is moving past the lateral portions of the work than when it is moving over the terminal portion. 90

8. A copying lathe having a tool and a revoluble work support arranged to hold a last with its terminal stub projecting substantially perpendicularly to the drive spindle of the support, and width grading mechanism comprising a fan-board, a feeler contacting therewith, means for adjusting the feeler for the width grade desired, and means for moving the feeler to a position corresponding to an extreme upward width 100 grade when the cutter is passing around the work support.

9. A copying lathe having a tool and a revoluble work support arranged to hold a last with its terminal stub projecting substantially perpendicularly to the drive spindle of the support, a fan-board, a feeler contacting therewith, means for adjusting the feeler for the width grade desired, and means for moving the feeler to a position 110 corresponding to an extreme upward width grade when the cutter is passing around the work support, comprising a lever connected to the feeler and means for swinging the lever.

10. A copying lathe having a tool and a revoluble work support arranged to hold a last with its terminal stub projecting substantially perpendicularly to the drive spindle of the support and width grading mechanism comprising a fan-board, a feeler contacting therewith, and means for moving the feeler to a position corresponding to an extreme upward width grade when the cutter is passing around the work support, com- 115 120 125 130

prising a member adjustably connected to the feeler for width grading adjustment, and cam mechanism for moving the member to produce the said extreme positioning of the feeler.

11. A copying lathe having a tool and a revoluble work support arranged to hold a last with its terminal stub projecting substantially perpendicularly to the drive spindle of the support and width grading mechanism comprising a fan-board, a feeler contacting therewith, and means for moving the feeler to a position corresponding to an extreme upward width grade when the cutter is passing around the work support, comprising a member adjustably connected to the feeler for width grading adjustment,

and cam mechanism for cyclically shifting said member alternately into positions corresponding to normal width grading position of the feeler and to extreme upward width grading position of the feeler, respectively.

12. That improvement in the art of manufacturing lasts which consists in revolving the stub of a last, left after the last turning operation, about an axis substantially perpendicular to the tread surface of the last, against a cutter, and guiding the work from a model or template to control the depth of cut.

In testimony whereof I have signed my name to this specification.

LAURENCE E. TOPHAM.
